INVENTOR

UNITED STATES PATENT OFFICE.

PETER J. SHRUM, OF MONACA HEIGHTS, PENNSYLVANIA, ASSIGNOR TO COLONA MANUFACTURING COMPANY, OF PITTSBURGH, PENNSYLVANIA, A CORPORATION OF PENNSYLVANIA.

THREAD PROTECTOR.

Application filed February 2, 1924. Serial No. 690,103.

To all whom it may concern:

Be it known that I, PETER J. SHRUM, a citizen of the United States, residing at Monaca Heights, in the county of Beaver and State of Pennsylvania, have invented certain new and useful Improvements in Thread Protectors, of which the following is a specification.

My invention consists of an improvement in thread protectors, and has for its object to provide such a device formed of a continuous integral ring having interior securing or attaching threads, an outwardly extending rounded or bulging portion, an inner coping or protecting shell portion, and an opposite terminal flaring portion, as shall be more fully hereinafter set forth.

The device is of the general class illustrated in a co-pending application of myself and Harold A. Henigen, Serial No. 648,493, and the blank is preferably formed from a section of seamless welded tubing, by a swaging or upsetting operation somewhat like that of our prior Patent No. 1,475,032 of November 20, 1923.

One preferred form of the device is illustrated in the accompanying drawing, in which:

Fig. 1 is a longitudinal sectional view through the threaded end portion of a pipe provided with a protector as applied;

Fig. 2 is an outer end view of the protector;

Fig. 3 is an enlarged partial sectional view of the cylindrical blank from which the device is made; and

Fig. 4 is a similar partial sectional detail view of the device, showing the several continuously annular features involved in the completed device.

The blank 2 from which the protector of this invention is made, is a cylindrical section of seamless or welded tubing, cut to length and preferably slightly larger in internal diameter than the outside diameter of the pipe 3 with which it is to be used. Said pipe is provided at the ends with the usual coupling threads 4, the protection of which in shipping, storage, etc., is the purpose of the present invention.

In forming the complete protector from the blank 2, it is desirable that it shall be provided with a series of securing threads

at its outer portion, of standard size and proper taper, to be screwed up tightly so as to bind on the outer threads 4 of pipe 3 when the device has been screwed on sufficiently for complete protection. To this end, the interior of the inner end portion is not threaded for a distance inwardly, indicated by the dimension letter *a*, Fig. 4, the remainder of the shell being threaded to its outer end for the remainder of its length, or for the combined length of dimensions *b* and *c*, respectively, except that portion of the flare which extends beyond the diameter. The effective holding threads 5 are those extending through so much of the middle portion of the protector as is indicated by *b*, approximating or slightly less in length than the unthreaded or overlapping portion *a*.

The remaining threaded portion, dimension *c*, is abruptly deflected outwardly, forming the inner non-contacting surface of the flaring rim 6. It will be observed that all that portion of the protector inwardly beyond the threaded part forms a protecting coping or overlapping shell which extends inwardly to about the point where the threads of pipe 4 merge into the outer surface or terminate, when the device is screwed up tight, as in Fig. 1. Also, that the outer terminal of rim 6 occupies a position substantially parallel with the opposite terminal 7, as the ends of the original blank were related to each other and to the longitudinal center, before forming the blank into the finished article.

The inner wall coping portion of the device, terminating in end 7, is left smooth as shown, and tapers substantially with the taper of the threads 5, providing a smooth inner annular wall surface 8 which assumes a close embracing position around the threads, as shown. Between such coping and the threads 5, is the outwardly rounded bulging ring 9, the inner wall of which is abruptly spaced away from the threaded zone of the protector and of the pipe, leaving a surrounding interior open space 10 and providing the outer rounded surface 11. This portion of the protector is of advantage in giving added bracing strength, and also provides an annular extended rounded ring on which the pipe may be easily rolled,

especially when equipped with a protector at each end.

The manufacture of the complete device involves endwise swaging or upsetting to effect the formation of the bulge 9, and also of the terminal flaring end 6, and also the relative contraction of the middle portion bearing the threads 5. Likewise, the longitudinal upsetting tends to condense and 10 thicken the wall, in connection with its diametrical reduction, so that ample excess stock is provided for cutting the threads without any weakening of the wall.

The several swaging operations on the 15 blank, with suitable dies, give it the desired tapered form, ready for cutting the thread, after which the terminal flare 6 is formed. This latter feature is a novel and useful one in thread protectors of this type, in that it 20 extends outwardly beyond the end of the pipe and efficiently protects the threads from injury, either by direct contact with any obstruction, or from the danger of a dent in the end of an ordinary straight wall protector.

The terminal flare 6 with the rounded bulging ring 9 beyond, also leaves an intervening annular channel or recess 12, providing a convenient grasping area for a 30 turning wrench or tongs, and assisting in keeping such tool in place.

By reason of its annular reinforcing enlargements, I am enabled to make the protector of metal of minimum gauge or thickness, due to its added bracing strength, and with corresponding economy. The device may be made in any desired size or dimensions; it is very strong and durable, well adapted to the purpose in view, and capable 40 of repeated use. It may be made in different proportions from those shown, or changed in detail construction by the skilled mechanic, but all such changes are to be considered as within the scope of the following 45 claims.

What I claim is:

1. A protector for a threaded member comprising an annular sleeve having an outwardly extending rounded bearing ring portion intermediate its ends and a tapering unthreaded coping portion with its inner surface adapted to be spaced beyond the threads of the threaded member, said sleeve being further provided with an interiorly threaded portion extending in the other direction beyond the bearing ring and terminating in an interior outwardly flaring unthreaded portion.

2. A threaded protector comprising an annular sleeve interiorly threaded for a portion of its length, another portion being provided with a rounded shoulder extending beyond the normal outer wall of the sleeve between the threaded portion and its inner end, and having an outwardly flaring terminal beyond the opposite end of the threaded portion.

3. A thread protector for pipes comprising a cylindrical tapered sleeve provided with a tapered interiorly smooth terminal coping portion merging into an outwardly bulging annular ring portion intermediate the ends of the sleeve, and a threaded portion extending from said outwardly bulging ring portion towards the other end of the sleeve, said sleeve terminating in a short interior flaring portion.

4. A thread protector for pipes comprising a cylindrical tapered sleeve provided with a tapered interiorly smooth coping portion, an outwardly bulging annular ring portion extending inwardly beyond the coping portion, and a threaded portion extending from said ring portion to its other end, the sleeve being there abruptly turned outwardly to form a flaring terminal.

In testimony whereof I hereunto affix my signature.

PETER J. SHRUM.
